United States Patent Office

Des. 221,965
Patented Sept. 21, 1971

221,965

SCOOTER

Francis C. La Jeunesse, 1196 Boulevard Way,
Walnut Creek, Calif. 94595

Filed Mar. 18, 1970, Ser. No. 21,961

Term of patent 14 years

Int. Cl. D12—11

U.S. Cl. D34—15

FIG. 1.

FIG. 2.

FIG. 3.

FIG. 4. FIG. 5.

FIG. 1 is a perspective view of a scooter showing my new design;

FIG. 2 is a side elevational view of the scooter of FIG. 1 with the rear wheel thereof rotated to a different position;

FIG. 3 is a top plan view thereof;

FIG. 4 is a front elevational view thereof; and

FIG. 5 is a rear elevational view thereof.

I claim:

The ornamental design for a scooter, as shown and described.
